US00D926680S

(12) **United States Design Patent** (10) **Patent No.:** **US D926,680 S**
(45) **Date of Patent:** **** Aug. 3, 2021**

(54) **CHARGING DOCK**

(71) Applicant: **JUUL Labs, Inc.**, San Francisco, CA (US)

(72) Inventors: **Guangping Wang**, Shenzhen (CN); **Jincheng Li**, Shenzhen (CN); **Wenlong Yang**, Huizhou (CN); **Jian Yao**, Shenzhen (CN)

(73) Assignee: **JUUL Labs, Inc.**, San Francisco, CA (US)

(**) Term: **15 Years**

(21) Appl. No.: **29/708,184**

(22) Filed: **Oct. 3, 2019**

(51) LOC (13) Cl. **13-02**

(52) U.S. Cl.
